ATTORNEY

UNITED STATES PATENT OFFICE.

EMMETT M. SIMS, OF LOUISVILLE, KENTUCKY.

SPARK-OBSERVER.

1,314,908.

Specification of Letters Patent. Patented Sept. 2, 1919.

Application filed December 21, 1918. Serial No. 267,780.

To all whom it may concern:

Be it known that I, EMMETT MARVIN SIMS, a citizen of the United States, residing in the city of Louisville, county of Jefferson, and State of Kentucky, have invented 5 a new and useful Spark-Observer, of which the following is a specification.

This invention relates to means for observing a spark in the ignition circuit of an 10 internal combustion motor.

In internal combustion, or explosive motors, in which power is obtained by the explosion of a gaseous mixture within the cylinders of the motor, the explosive mixture is 15 usually ignited by means of an electric spark.

A high tension electric current in jumping across a gap in its circuit will produce a spark capable of igniting a combustible gas.

20 A spark plug is a device adapted to be removably positioned in an opening in the wall of a cylinder of an internal combustion motor, by means of which an electric spark may be produced within the cylinder.

25 The electric conductor, known as the firing pin, leading through the plug, to the gap, is well insulated from the body of the plug and the conductor leading from the gap is connected to the body of the plug which in 30 turn is grounded on the frame of the motor.

One pole of the source of electric current, usually a magneto generator, is grounded on the frame of the motor and the other pole connected with a device styled a timer, 35 or distributor. A wire leads from a segment on the timer to a connection with the firing pin of a corresponding spark plug. The timer rotates in synchronism with the motor and closes the respective circuit at the

40 proper moment to cause a spark in the respective cylinders. Experience has shown that many motor troubles may be diagnosed by observing the quality of the spark. As the spark which ignites the charge is within 45 the cylinder, it cannot be seen, consequently another spark, either in series or in parallel with the ignition spark must be caused where it can be seen. Mechanicians are in the habit of placing a tool, such as a

50 screw driver upon the end of the firing pin of the plug and bringing the end thereof close to the motor and observing the spark which occurs. Plugs have been produced with a second gap in the body thereof, an 55 opening or window being provided through which the spark may be observed. Devices

have been produced which are provided with a spark gap and which may be attached to the spark plug, being interposed between it and the ignition lead coming from the timer. 60 These devices serve their purpose, but an objection to them, in connection with a motor vehicle, is that they can be utilized only when the vehicle is standing still, and that then it is necessary to raise the hood which 65 covers the motor, to obtain access to the spark plug or the devices associated with them.

An object of this invention is to provide a device which may be located in any convenient position, in a motor vehicle, on the dash board thereof, where it will be within convenient reach of the chauffeur, and wherewith the motor may be tested under service conditions while the vehicle is moving. 70

A further object is the provision of a device, such as characterized, which will be economical in construction, easily operated, and efficient and durable in service. 75

With the foregoing and other objects in view, the invention consists of the novel construction and arrangement of parts illustrated in the accompanying drawing, which forms a part of this specification, wherein 80 is set forth an embodiment of the invention, but it is to be understood that such changes and modifications may be resorted to as come within the scope of the appended claims.

In the drawing wherein similar reference 85 characters designate like parts in the several views, Figure 1, is a perspective view of an embodiment of the invention, and Fig. 2 a rear elevation thereof.

The invention comprises a panel board 90 —10— adapted to be secured by suitable means such as screws —11— in any desired position. A flange —12— projecting inward from the ends and top of the board serves to space it from the wall against which it is 100 placed, thus affording room for connections which are to be made on the back thereof. The panel is provided with a sight opening or window —13—. Two binding posts —14, 15— are positioned respectively on each side 105 of the window. Electrodes —16, 17— are secured respectively to the binding posts 14, 15, and extend toward each other, their adjacent ends being separated by a spark gap —18— which lies opposite the window, 110 through which it may be observed. A ground wire —19— attached to the binding

post, 14, is led to a connection with the frame. A plurality of connecting means which comprise nuts —20—, which are threaded on screws —21—, the screws being integral with posts —22— erected on the face of the board, are positioned on the rear of the panel, one to correspond with each cylinder of the motor, and an insulated connecting wire —23— extends from each of them to and is connected with the spark plug of a corresponding cylinder of the motor. If now, when the motor is running a connection is established between the ground wire 19, and one of the wires 23, the high tension electric current will divide at a spark plug, and a portion of it travel over the wire 23, jump the gap 18, and pass on to the frame and to the generator. Any suitable means may be provided therewith to establish a connection between the ground wire and a connecting wire. The means which at the present time seems preferable to me comprises a flexible insulated conductor —24— connected with the binding post 15, on the front panel and provided with a tip —25— whereby it may be engaged with either one of the posts 22 erected on the panel as shown in dotted lines in Fig. 1, each of the posts 22 being provided with a perforation —26— for its reception. The posts 22 are held in position by the nuts 20. It is to be understood that the top of the flexible connector is inserted in one of the posts 22 only when it is desired to ascertain the character of the spark in the cylinder, and that this can be done without stopping the car, or of the chauffeur having to leave his seat. When not in use, the tip may be placed in a hole —27— in the upper edge of the panel.

When the spark gaps are properly adjusted, 40 a clear blue white spark will be seen. A regular spark indicates a good spark plug. An irregular spark indicates defective insulation, usually in the spark plug. If the motor is exploding irregularly and the spark 45 is clear, it indicates that the mixture is poor. If there is a "knock" in the motor it will be intensified when the "observer" is plunged in on the circuit, thus the cylinder in which it occurs may be located. 50

Having thus described my invention so that any one skilled in the art pertaining thereto can make and use the same,

I claim:

1. In combination with the power plant of 55 a motor vehicle, a panel board, a pair of electrodes mounted thereon and having a spark gap between their adjacent terminals, a plurality of posts erected on said board, said posts being connected respectively with 60 corresponding spark plugs in the motor, a flexible connector attached to one of said electrodes and adapted to be connected with any one of said posts, the other electrode being grounded. 65

2. In combination with a multi-cylinder internal combustion motor, a panel board, a pair of electrodes mounted thereon and having a spark gap between their adjacent ends, 70 a flexible connector provided with a tip connected to one of said electrodes, the other electrode being grounded on the motor, a plurality of posts erected on the panel, each of said posts having a perforation adapted 75 to receive the tip of the flexible connector, and each of the posts being connected with a corresponding spark plug in the motor. 75

EMMETT M. SIMS.
